ENGINE HOUSING FOR LOCOMOTIVES
OR THE LIKE

Joseph M. Milheizler, Pittsburgh, Pa., assignor to
H. K. Porter Company, Inc., Pittsburgh, Pa., a
corporation of Pennsylvania

Application March 15, 1944, Serial No. 526,633

2 Claims. (Cl. 105—62)

1

This invention relates to a housing for the engine of a locomotive, particularly a locomotive driven by an internal-combustion engine, either directly or through an electric generator and motor.

Locomotives driven by internal-combustion engines have come into extensive use, particularly around industrial plants and for yard service on railroads. The enclosure heretofore provided for the engine or power plant for such locomotives has been a more or less make-shift structure, largely an adaptation of a conventional automobile hood. It is the object of my invention to provide an improved engine housing for locomotives or the like, so constructed as to provide complete accessibility to the engine as well as free circulation of cooling air therethrough. Further objects of the invention are to provide a housing having a good appearance and ample strength and rigidity to withstand the relatively rough service to which rolling stock is usually subjected. Another object is the provision of an engine housing of simple construction which may be produced at relatively low cost.

In a preferred embodiment, my novel engine housing comprises a frame composed principally of spaced bottom rails, front and rear posts standing thereon and top rails carried by the posts. Front and rear arch members carried by the top rails support a roof composed of a center panel and downwardly curving side panels hinged at their lower edges to the top rails. The center roof panel has ventilating ports provided with covers pivoted thereon and carries operating means common to the several covers. Doors hinged to the posts and additional doors slideable on the rails constitute substantially the entire side walls of the housing. A front-end closure is secured to the front posts and constitutes a continuation of the sides and roof. The front-end closure is provided with a window for admitting cooling air. A plurality of shutter vanes are pivotally mounted inside the window for controlling the air and each vane has one edge shaped to constitute a grille-bar when the vanes are in open position.

The novel features and advantages of the invention may be more clearly understood from a consideration of the following detailed description referring to the accompanying drawings illustrating a preferred embodiment. In the drawings,

Figure 1 is a side elevation of an engine housing according to my invention;

Figure 2 is a plan view thereof;

Figure 3 is a front elevation;

Figure 4 is a partial sectional view taken along the line IV—IV of Figure 1;

Figure 5 is a rear elevation of the shutter vanes and their supporting frame;

2

Figure 6 is a transverse section therethrough taken along the plane of line VI—VI of Figure 5;

Figure 7 is a partial section through one side of the housing, taken along the plane of line VII—VII of Figure 1;

Figure 8 is a partial section through the roof taken along the plane of line VIII—VIII of Figure 1;

Figure 9 is a plan view of a portion of the roof, to enlarged scale, showing one of the ventilating ports and its cover;

Figure 10 is a longitudinal section taken along the plane of line X—X of Figure 9;

Figure 11 is a partial section through the lower portion of one side of the front-end closure, taken along the line of plane XI—XI of Figure 1; and

Figure 12 is a partial section through a headlight supporting ring, taken along the plane of line XII—XII of Figure 3.

Referring in detail to the drawings, my engine housing indicated generally at 10 includes a frame made up of spaced bottom rails or sills 11 and 12, front posts 13 and 14, and rear posts 15 and 16, upstanding thereon. The front and rear posts support top rails or beams 17 and 18. Front and rear arch members 19 and 20 are supported on the rails 17 and 18. The rails 11 and 12 are composed of flanged plates having angle bars 21 welded to the lower edge thereof. Angle bars 22 are welded to the flange of the rails which is disposed uppermost. The posts 13 and 14 are flat bars welded to flanged side panels 13a and 14a as shown in Figure 4. The posts 15 and 16 are similar in construction to the rails 11 and 12, having angle bars 23 welded to the rear edge thereof. The rails 17 and 18 are similar to the rails 11 and 12 except that they have flanges at both edges and have angle bars 24 welded to the lower flange thereof. The arch member 19 is a flat bar and the member 20 an angle, both of which are bent to appropriate shape as shown in Figures 3 and 7.

The housing 10 is adapted to be installed on a floor or deck of a locomotive adjacent the operator's cab. To this end, the angle bars 21 at the lower edges of the bottom rails 11 and 12 may be welded to the deck plate the upper surface of which is designated by the chain line 25 in Figure 1. Similarly, the angle bars 23 and the arch member 20 may be welded to the cab wall, the outer surface of which is designated by chain line 26 in Figure 1. The frame described above has sides formed substantially exclusively by doors 27, 28, 29, 30, a roof including a center panel 31, and side panels 32 and 33 curving downwardly therefrom, and a front-end closure 34 which constitutes a rounded continuation of the sides and roof. The center panel 31 has down-turned flanges welded to angle bars 35 and 36 extending

longitudinally of the housing between the arch members 19 and 29. The flanges of the panel 31 are provided with louvers 31a spaced along the length thereof. The panel 31 also has a plurality of ventilating ports 37 spaced therealong each of which is provided with a cover 38 having clips 39 pivotally engaging the forward edge of the port. Lugs 40 are welded to the covers 38 and lugs 41 are welded to the lower surface of the panel adjacent the forward edges of the ports. Tension springs 42 secured to the lugs normally hold the covers closed. A rock shaft 43 journaled in bearings 44 secured to the lower surface of the panel 31 has cams 45 thereon bearing on the lower surface of the covers 38. A lever 46 secured to the shaft 43 permits it to be rotated manually whereby the cams 45 cause the covers 38 to be tilted upwardly about their forward edges. This permits egress of cooling air admitted to the housing through a window in 20 the front-end closure to be described shortly.

The doors 27 and 30 are flanged panels having ventilating louvers 47, the doors 27 being hinged to the side panels 13a and 14a and the doors 30 being hinged to rear posts 15 and 16. The hinges, indicated at 48, are of the concealed type including a U-shaped strap 49 welded to one flange of the door and having lugs 50 cooperating with lugs 51 secured to the posts and adapted to receive a pin 52 as shown in Figure 4. The flanges of the panels 13a and 14a and the posts 15 and 16 are cut out as at 53 to permit the doors 27 and 30 to be opened wide.

The doors 27 and 30 are provided with locking levers 54 actuated by handles 55 and adapted to engage behind the edges of doors 28 and 29.

The doors 28 and 29 are generally similar to the doors 27 and 30 but, instead of being hinged, are arranged for sliding movement. Each of the doors 28 and 29 has a pair of guide and bearing blocks 56 welded inside the lower flange thereof, and a pair of guide blocks 57 welded inside the upper flange. The blocks 56 and 57 have slots adapted to receive the vertical flanges of the angle bars 22 and 24. Each block 56 also has a bearing ball 58 positioned in a hole 59 drilled through the block and the lower flange of the door. A spring 60 is disposed behind the ball 58 and a plug 61 is threaded into the hole to hold the spring and ball in place. Each block 56 also has a thumb screw 56a threaded into a hole extending from the inner side thereof, the screw being adapted to engage the vertical flange of the angle bar 32 to clamp the door in position. When the screws 62 have been released, the doors 28 and 29 may be slid freely along the angle bars 22 and 24 which serve as guide rails therefor.

From the above description, it will be apparent that the sides of the housing 10 are unobstructed between the panels 13a and 14a and the rear posts 15 and 16. As a result, when the doors 27 and 30 are open, the doors 28 and 29, respectively, may be slid along the rails to the positions occupied by the doors 27 and 30 when closed. Alternatively, both the doors 28 and 29 may be slid forwardly or rearwardly. It will be evident that this arrangement provides ready access to any point of the engine or power plant within the housing. At the same time, the location of the hinged doors 27 and 30 at the extreme front and rear of the sides, leaves them in out-of-the-way positions when open as compared, for example, to a construction in which all doors are hinged to vertical supporting posts.

The side panels 32 and 33 of the roof have their

lower edges hinged to the upper rails 17 and 18 by hinges 62 similar to the hinges 48. The upper edges of the panels are secured to the angle bars 35 and 36 by bolts 63. On removing these bolts, the panels may be swung outwardly, leaving the greater portion of the roof open to admit light to the interior of the housing or provide access thereto from above.

The front end closure 34 is preferably in the form of a rounded shell which constitutes a one-piece continuation of the sides and roof. The closure has a raised portion 64 corresponding to the center panel 31 on the roof which merges into the front thereof as shown in Figure 1. A headlight supporting ring 65 is welded in this raised portion and is adapted to receive a headlight 66. A rail 67 similar to the bottom side rails 11 and 12 extends around the bottom of the closure. The front-end closure is secured to the remainder of the housing by bolting to the posts 13 and 14 and angle bars 21 so that it may readily be removed, if desired.

A window 68 is formed centrally in the front of the closure below the headlight 66. Just behind the opening is positioned a frame 69 having a plurality of shutter vanes 70 pivoted thereto. The frame 69 is composed of angle bars welded together. The vanes 70 are composed of heavy-gauge sheet having one edge flanged as shown in Figure 5. Pivot pins 71 and 72 welded to opposite ends of the vanes pass through holes in the upper and lower members of the frame 69. The edges of the vanes remote from their pivot pins have lugs 73 pivoted to a control bar 74. The side members of the frame 69 are notched at 75 to permit sufficient movement of the bar 74 to turn the shutter vanes to closed position as shown in chain lines in Figure 6. The exterior appearance of the vanes when in closed position is as shown in Figure 3. When the vanes are in open position as shown in Figure 6, the flanged edges thereof present the appearance of grille-bars. By this construction, I eliminate the usual grille for protecting the radiator installed behind the shutter vanes since the latter are made of metal of sufficiently heavy gauge to make them strong enough to serve effectively as a protective grille. Any suitable mechanism may be provided for operating the bar 74 from the cab to adjust the shutter vanes as may be desired to maintain the proper temperature of the water in the cooling system of the engine.

It will be apparent from the foregoing description and explanation that my invention provides a housing for the engine or power plant of a locomotive driven by an internal combustion engine, having numerous advantages over the engine enclosures previously provided on such locomotives. My housing has an attractive appearance and is sturdily constructed so as to withstand the shock and vibration incident to the operation of a locomotive. In addition, the combination of hinged and sliding doors forming substantially the entire sides of the housing and the hinged roof panels provides easy access to any part of the engine or power plant requiring attention. The entire construction, nevertheless, is relatively simple, being composed almost entirely of plate and standard structural members so that it can be readily fabricated at relatively low cost. Ample provision is made for the circulation of cooling air through the housing, as well as the control thereof in accordance with atmospheric temperatures existing from time to time. Although I have illustrated and described but

a preferred embodiment of my housing, it will be recognized that changes in the details or arrangement thereof may be made without departing from the spirit of the invention or the scope of the appended claims.

I claim:

1. An engine housing for locomotives or the like comprising spaced bottom rails, front and rear posts extending upwardly from said rails, upper rails supported on said posts, a roof carried on said upper rails, front and rear arch members extending between said upper rails, said roof being supported on said arch members and including a pair of downwardly curving side panels each hinged at its lower edge to one of said 15

top rails and a front end closure secured to the front arch member and the front posts, said closure forming a continuation of said panels.

2. An engine housing for locomotives or the like comprising spaced bottom rails, front and rear posts extending upwardly from said rails, upper rails supported on said posts, a roof carried on said upper rails, and front and rear arch members extending between said upper rails, said roof being supported on said arch members and including a center panel and a downwardly curving side panel on each side of the center panel, said side panels being hinged at their lower edges to said upper rails, respectively.

JOSEPH M. MILHEIZLER.
